BOTTLE

Joseph M. Kennedy, St. Louis, Mo.

Application November 2, 1931. Serial No. 572,502

4 Claims. (Cl. 215—57)

This invention relates generally to bottles and more specifically to an improved bottle provided with means for measuring predetermined amounts of liquid therefrom, the predominant object of the invention being to provide a bottle of this type which is so constructed that it will not be necessary for the user of the bottle to be provided with a spoon or other measuring device for the purpose of measuring predetermined amounts of the liquid contents from the bottle.

As is quite generally known, medicines and other liquids which are dispensed in bottles usually are used by withdrawing predetermined amounts of the liquid from the bottles, in the case of medicines these amounts ordinarily being in doses of one spoonful or more of the medicine. It frequently happens that the user of such a bottle is not provided with a spoon, as in the home the spoons may be in a remote part of the house, while in the case of a person who is required to carry a bottle of medicine about on his person a spoon is seldom at hand, because of the inconvenience of carrying and using the same.

To obviate the necessity that a person be provided with a spoon of the proper size for measuring out amounts of liquid in a bottle, I have devised the bottle disclosed herein, which, briefly stated, is provided with a measuring compartment, which communicates with the interior of the neck portion of the bottle. In use, the bottle is tipped so as to cause the measuring well or compartment to receive liquid from the body portion of the bottle, after which an adjustable cork is moved, and the bottle is returned to its upright position to cause the main body of liquid in the bottle to be returned to the body portion of the bottle. In this manner, a small body of liquid is trapped in the measuring well or compartment and segregated from the remainder of the liquid within the bottle. The user may then pour out the contents of the measuring well or compartment into a receptacle or may raise the bottle to the lips and discharge the contents of the measuring well or compartment into the mouth, whereby a predetermined amount of the liquid will be taken.

Figure 1 is a vertical section of the upper portion of a bottle constructed in accordance with this invention;

Figure 2 is a view similar to Figure 1, but showing the bottle when it has been tipped to fill the measuring well or compartment;

Figure 3 is a view similar to Figures 1 and 2,

but showing the bottle after it has been returned to its upright position after the tipping operation illustrated in Figure 2 and after the position of the cork of the bottle has been altered;

Figure 4 is a view similar to Figures 1, 2, and 3 illustrating the manner in which the measured liquid is withdrawn from the measuring well or compartment; and

Figure 5 is a plan view of the improved bottle.

In the drawing, wherein is shown for the purpose of illustration merely one embodiment of the invention, A designates my improved bottle generally, said bottle comprising a body portion B and a neck portion C. The body portion B of the bottle A is constructed in the manner common to bottles of the type to which this invention relates, and, therefore, in the drawing the lower portion of said body portion has been broken away to conserve space.

The neck portion C of the bottle A is so formed that a measuring well or compartment 1 is provided. This measuring well or compartment 1 is formed by bulging the wall of the neck portion C of the bottle outwardly, as shown in the drawing, and preferably the measuring well or compartment is of greater dimension in the direction of the width of the bottle than it is in the direction of the depth of said bottle, as shown clearly in Figure 5. In this respect, the shape of the measuring well or compartment 1 follows the horizontal sectional shape of the body portion B of the bottle, which, as shown in Figure 5, is of greater width than depth. The cavity 1' within the integrally formed measuring well or compartment is in direct communication with the interior of the body portion B of the bottle through the instrumentality of the passageway through the lower portion of the neck portion C. A portion of the neck portion C of the bottle extends above the measuring well or compartment 1, and this portion of said neck portion is provided with external screwthreads 2, which serve a purpose to be hereinafter mentioned.

Extended into the neck portion C of the bottle, so that it normally passes through the measuring well or compartment 1, is a closure element 3, which is formed of cork or any other suitable material. The closure element 3 is of elongated form, and preferably is of circular cross-section, as indicated in Figure 5. The upper portion of the closure element is separated from the main body of said closure element by an annular depression or groove 4, so as to provide a gripping

portion 5, which is extended beyond the upper end of the neck portion of the bottle. If desired this gripping portion may be roughened, or, if preferred, a knurled metal cap 6 may be forced over this gripping portion to provide same with the desired roughened surface.

The wall of the lower portion of the neck portion C of the bottle A is provided with a tapered inner face, as indicated at 7, so that the passageway through said lower portion of said neck portion tapers from one diameter at the top of said portion to a slightly smaller diameter at the lower end of said portion. Also, the closure element 3 is provided with a lower portion 3', which substantially corresponds in shape and dimensions to the shape and dimensions of the passageway referred to. When the closure element 3 is in the position where it seals the body portion of the bottle so as to prevent the loss of any of the contents thereof, the portion 3' of said closure element is firmly located in the tapered passageway formed through the lower portion of the neck portion C, as shown in Figure 1. It will be noted that the passageway 8 through the upper portion of the neck portion of the bottle is of greater diameter than the closure element; hence an annular liquid discharge opening or passageway is present between the wall of the passageway 8 and the circumferential face of the closure element. Also, when the closure element is in its bottle-sealing position, as illustrated in Figure 1, I provide a removable bottle cap 9, which embraces the upper portion of the closure element and is provided with screwthreads that engage the screwthreads 2 at the top of the neck portion of the bottle.

When my improved bottle is not in use, it is disposed in an upright position, as illustrated in Figure 1, and the closure element 3 is arranged in the position shown so as to close the lower portion of the neck portion of the bottle and prevent passage of liquid from the body portion of the bottle.

Assuming now that it is desired to withdraw from the bottle a predetermined amount of the liquid contained therein, the bottle will be tilted slightly and the closure element will be moved outwardly, as indicated in Figure 2, so as to remove the portion 3' of said closure element from the tapered passageway in the lower portion of the neck portion of the bottle. This will permit liquid in the body portion of the bottle to flow into the measuring well or compartment 1, and when an amount of liquid sufficient to fill the lowermost portion of the measuring well or compartment 1 has passed into said measuring well or compartment, the closure element 3 is moved inwardly, so that the portion 3' of said closure element closes the passageway through the lower portion of the neck portion of the bottle. With the closure element so positioned, the liquid which passed into the measuring well or compartment 1 of the bottle is trapped therein, as illustrated in Figure 3, and, because of the annular opening between the wall of the opening 8 in the upper portion of the neck portion of the bottle and the circumferential face of the closure element 3, the liquid within said measuring well or compartment may be poured therefrom into a receptacle, or the upper end of the neck portion of the bottle may be placed to the lips and the contents of the measuring well or compartment discharged into the mouth.

The measuring well or compartment 1 is so proportioned that when liquid which is caused

to pass into said measuring well or compartment from the body portion of the bottle fills the lower portion of the measuring well or compartment to the level of the lowermost point of the passageways through the upper and lower neck portions when the bottle is held in a substantially horizontal position, such amount of liquid will represent precisely a teaspoon of liquid. This is true whether the bottle is held so that the greater dimension *a* or the lesser dimension *b* of the measuring well or compartment is disposed in a substantially vertical position, as, if the lesser dimension *b* of the measuring well or compartment is disposed in the vertical position, the proper volume of liquid will be trapped in the relatively shallow lower portion of the measuring well or compartment, due to said trapped liquid being in the form of a body of liquid of greater area.

By shaping the measuring well or compartment 1 as shown in Figure 5, and arranging said measuring well or compartment with respect to the body portion of the bottle, as shown in said view, the bottle may be held so that the lesser dimension *b* of the bottle is vertical when the amount of liquid within the body portion of the bottle has been greatly reduced. In this manner the final amount of liquid may be drained into the measuring well or compartment from the body portion of the bottle without tipping the bottle to such an angle that the liquid would pass through the opening 8 before the proper amount of liquid has been measured in the measuring well or compartment.

The closure element 3 is provided with a rounded face 3^a, which may be placed against the upper lip when liquid is being discharged from the measuring well or compartment into the mouth, as in this manner the bottle neck is properly positioned with respect to the mouth. Also, this rounded face 3^a permits of the closure element being pressed against the upper lip without discomfort, in order to move said closure element to one side of the opening 8, and thus increase the size of the discharge passageway through which the liquid is discharged. Furthermore, because of the shape of the rounded face 3^a, a user of the bottle may discharge liquid into his mouth without tilting his head backward to an uncomfortable degree, and the shoulder at the top of the annular groove 4 will serve to prevent liquid from traveling longitudinally along the closure element toward the outer end thereof, and will deflect the liquid into the mouth of the user of the bottle. An important feature of the invention is that the neck of the bottle does not come into contact with the mouth of the user of the bottle when measured liquid is being discharged directly into the mouth. Instead the outer end of the closure element is caused to contact with the upper lip above the mouth, whereby such use of the bottle is rendered more sanitary.

It is obvious that if desired the wall of the measuring well 1 may be provided with markings which would indicate the proper levels of the liquid therein to obtain predetermined amounts of liquid.

The cap 9 is of such size that it may be employed as a measuring receptacle into which portions of the contents of the bottle may be poured for measuring said portions, when for any reason it is not desired to employ the measuring well 1. Also the cap 9 may be provided with

markings to indicate the levels of predetermined amounts of liquid.

While I have described the contents of my improved bottle as liquid it is to be understood that such contents may be any free running substances which might be conveniently sold in bottles.

I claim:

1. A bottle including a body portion and a neck portion having a discharge mouth at the outer end thereof, a measuring well arranged in communication with said body portion through the instrumentality of a passageway, and a closure element extended through said measuring well and provided with a portion which seals said passageway between the body portion of the bottle and the measuring well, said closure element being extended through the mouth of the bottle to a point outside of said bottle so as to provide a portion of said closure element which may be grasped and manually manipulated by a user of the bottle.

2. A bottle including a body portion and a neck portion, a measuring well forming a part of said neck portion and arranged in communication with said body portion through the instrumentality of a passageway formed through a portion of said neck portion, a closure element extended through said measuring well and provided with a portion which seals said passageway between the body portion of the bottle and the measuring well, said measuring well being provided with a discharge opening through which said closure element passes and which is sufficiently larger than the cross-sectional dimension of said closure member to provide a liquid discharge space between the wall of said opening and the face of said closure element, and a gripping portion associated with said closure element.

3. A bottle including a body portion and a

neck portion, a measuring well forming a part of said neck portion and arranged in communication with said body portion through the instrumentality of a passageway formed through a portion of said neck portion, a closure element extended through said measuring well and provided with a portion which seals said passageway between the body portion of the bottle and the measuring well, said measuring well being provided with a discharge opening through which said closure element passes and which is sufficiently larger than the cross-sectional dimension of said closure member to provide a liquid discharge space between the wall of said opening and the face of said closure element, and a gripping portion associated with said closure element and extended outwardly beyond said measuring well.

4. A bottle including a body portion and a neck portion, a measuring well forming a part of said neck portion and arranged in communication with said body portion through the instrumentality of a passageway formed through a portion of said neck portion, a closure element extended through said measuring well and provided with a portion which seals said passageway between the body portion of the bottle and the measuring well, said measuring well being provided with a discharge opening through which said closure element passes and which is sufficiently larger than the cross-sectional dimension of said closure member to provide a liquid discharge space between the wall of said opening and the face of said closure element, a gripping portion associated with said closure element and extended outwardly beyond said measuring well, and a cap secured to said neck portion and arranged to embrace the extended gripping portion of said closure element.
